UNITED STATES PATENT OFFICE.

BERNARD KWARTIN, OF PHILADELPHIA, PENNSYLVANIA.

HOLDER FOR TELEPHONE RECEIVERS.

Application filed November 16, 1926. Serial No. 148,630.

My invention relates to new and useful improvements in holders for telephone receivers, and has for its primary object to provide an exceedingly simple and effective device of this character which may be readily and quickly attached to or detached from a telephone of the type that are set on desks, tables and the like.

Another object of the invention is to provide an attachment for telephones which attachment will hold the receiver whereby the hands of the user are free for writing or other purposes, when the telephone is resting upon a suitable support, or leaving one hand free if it is desired that the telephone be held in the other hand or transported from one place to another.

Another object of the invention is to provide a unique method of holding the telephone switch in a closed position, and permits the locking of said switch in such position.

A further object is to provide means to prevent tipping of the telephone due to the extended weight of the telephone receiver, the said means providing for the attachment of a pad holder whereby memoranda may be jotted down by the user.

A still further object of the invention is to so construct the holder that it will be inexpensive in the cost of manufacture, although strong and durable.

With these and other ends in view, this invention consists in the details of construction and combination of elements herein-after set forth and then specifically designated by the claim.

In order that those skilled in the art to which this invention appertains, may understand how to make and use the same, I will describe its construction in detail, referring by numerals to the accompanying drawings forming a part of this application, in which:

Fig. 1, is a front elevation of a telephone and my holder for the receiver attached thereto.

Fig. 2, is a plan view thereof.

Fig. 3, is an edge view of the telephone switch holder removed from the device.

Fig. 4, is a side elevation thereof.

Fig. 5, is an end view of the same.

Fig. 6, is a bottom plan view of the stabilizer and pad holder.

In carrying out my invention as herein embodied, 7 represents a telephone of desk type, or one which may be moved from

place to place and set upon a suitable supporting surface, and includes the base 8, the body 9, the mouth piece or transmitter 10 and the switch arm 11, all of ordinary construction. 60

To the body of the telephone is secured my improved holder for the receiver, comprising a clamp 12 consisting of what I term, a stationary clamp member 13 and a movable clamp member 14, the latter being hinged or otherwise suitably connected with the stationary clamp as at 15, and temporarily or normally held in place by means of a fastening device 16, such as a screw. 65 It might be well to state at this point that both clamp members have semi-circular parts which pass about the telephone body. From one end of one of the clamp members, as the stationary clamp member 13, projects 70 an extension 17 which underlies the switch arm 11, and the outer end of this extension is provided with a downwardly projecting nose or hook 18, preventing accidental end-wise withdrawal of the switch arm holder, 75 to be presently described.

With the opposite end of one of the clamp members, preferably the one provided with the extension, is integrally formed an upwardly projecting arm 19, which extends 80 obliquely to a line drawn through the center of the switch arm 11, or in other words, it extends to one side and forwardly of the telephone instrument so that its upper end will be in a position close to that occupied 85 by the ear of a user when speaking into the transmitter. The upper outer end of the arm 19 carries a cradle 20 for the telephone receiver 21, and said cradle consists of the substantially horizontal finger 22 integrally 90 formed with the arm 19, and a number of spring clips 23 or their equivalent, mounted on the finger 22 and adapted to receive the telephone receiver. 95

The switch arm holder consists of two 100 stems 24 and 25 with their inner ends hinged together, as at 26, and the stem 24 has its upper end turned backward upon itself in spaced relation to form the hook 27 for engagement or registration with a portion of the switch arm 11, and if found desirable, the turned back portion may be provided with an eye 28 at right angles to said turned back portion. Adjacent the lower end of the stem 24 is formed a slightly 105 upward lug 29 to engage the under edge of the extension 17, and thus hold the switch 110

2
arm 11 down or in a closed position, but when it is desired to use the telephone, and therefore permit the switch arm 11 to raise or assume an open position, the holder is 5 swung outward sufficiently to disengage the lug 29 from the extension 17. The stem 25 is shorter than the stem 24 and has an eye 30 formed at right angles thereto at its outer end so that when the shorter stem 25 is 10 swung around into the position shown in dotted lines in Fig. 4, said eye 30 will align with the eye 28, and a padlock or other fastener may be attached to said eyes, and thus prevent unauthorized use of the telephone. 15 In order that the stem 25 may be swung into the position shown in dotted lines without interfering with the parts, an offset 31 is formed in said stem adjacent its hinged end, thus providing a recess for registration with 20 the lug 29.

In order to prevent the telephone instrument from tipping over due to the overhanging weight of the telephone receiver, I provide a stabilizer 32 having a clamp 33 at its inner end and including a stationary clamp element or member 34 and a movable clamp member 35 preferably hinged at 36 to a suitable portion of the stationary member, and temporarily or normally held in closed position by means of a fastening device 37, such as a screw, and the outer end of this stabilizer engages the support on which the telephone instrument rests at a point approximating the center of gravity of the telephone receiver. A standard 38 has one end attached to the stabilizer, and the upper end is provided with a crotch in which a portion of the clamp 12 rests, thus preventing the receiver holding arm from sliding down the 40 telephone body.

On the stabilizer is mounted a plate 39 having a paper clamp 40 and pencil clips 41

attached thereto so that a pad or sheets of paper 42 and a pencil 43 may be held in place ready for use. 45

Of course I do not wish to be limited to the exact details of construction as herein shown as these may be varied within the limits of the appended claim without departing from the spirit of my invention. 50

Having thus fully described my invention, what I claim as new and useful is:

A telephone attachment comprising a clamp adapted to encircle the body of a telephone instrument, an arm projecting upwardly and forwardly from said clamp, a substantially horizontal finger at the upper end of said arm, means carried by said finger to form a cradle to hold the receiver of the telephone, an extension projecting from the 55 clamp so as to underlie the switch arm of the telephone, a holder comprising two stems hinged together so as to be foldable, one upon the other, one of said stems having a hook to engage the switch arm, a lug to 60 engage the extension, and an eye, the other of said stems having a recess for registration with the lug when in a folded position and an eye for alignment with the eye on the first stem whereby a locking device may be 65 attached to prevent unauthorized use of the telephone, a stabilizer adapted to be clamped to the body of the telephone with a portion extending beyond the telephone base and 70 engaging the surface on which said telephone rests to prevent tipping of said telephone, and a standard attached to the stabilizer and having a fork at its upper end to 75 engage a portion of the receiver holding arm to prevent downward movement of said arm. 80

In testimony whereof, I have hereunto affixed my signature.

BERNARD KWARTIN.
